No. 1721

Daniel Moore, of Brooklyn, New York.
Letter Patent, No 1,721, Dated July 24. 1862.

The schedule referred to in these Letter Patent and making part of the same.

Nes 1721

To all whom it may concern:

Be it known that I, Daniel Moore of Brooklyn, in the County of Kings, and State of New York, have invented and made a certain new and original Ornamental Design, for the handles of Pistols; and I do hereby declare the following to be a full, clear and exact description of the same, reference being had to the annexed photograph thereof:

The rear of the said pistol handle a, is to be almost a semi-circle, coming around with a curved end to a rounding bow between the handle and the projection b, containing the trigger. This projection b, is curved forward from the said bow and the front side of said projection is curved inwards as shown: —

The handle a, and projection b, are rounded so that a section, through the handle at any part would be almost in the form of a circle. The design of this shape and configuration of the handle and trigger guard is highly ornamental and neat, at the same time not interfering with the proper grasp of the handle.

That I claim and desire to secure by Letters Patent is the ornamental design of the shape and configuration of the curved handle a, and trigger guard or projection b, as specified and represented.

In witness whereof I have hereunto set my signature this twenty-fourth day of January 1863,

Witnesses.
